DISPLAY CONTAINER

Walter J. Tyrseck, Montville, Conn., assignor to
 Robertson Paper Box Co., Inc., Montville, Conn.,
 a corporation of Connecticut

Application November 30, 1948, Serial No. 62,610

4 Claims. (Cl. 206—45)

1

This invention relates to improvements in display containers. More particularly, the invention is concerned with providing a display container or stand adapted to sit upon a counter or in other suitable location and hold a plurality of articles to be displayed for sale.

The invention contemplates the formation of such a container with built-in partitions, the container *per se* being formed from a single blank and being adapted to mass production and to shipment to the customer in knocked-down or flat condition. Ordinarily, the container will be made of paper, pasteboard, or like material, because of its economy and adaptation to manufacture on existing high-speed automatic machinery.

For a full understanding of the invention, a detailed description of the container will now be given in connection with the accompanying drawing and the features forming the invention will then be specifically pointed out in the appended claims.

In the drawing:

Figure 1 is a flat view of the container blank; Figure 2 is a view showing the container in the collapsed condition in which shipped to the customer;

Figure 3 is a front elevation of the container as set up and indicating the position of the articles to be displayed and certain other features in phantom;

Figure 4 is a section on the line 4—4 of Figure 3;

Figure 5 is a detail view showing a card for use with the display container proper, as shown in previous figures; and

Figure 6 is a perspective view showing the display container and display card, together with an outer box or carton in which the display container and contents may be shipped.

In the specific embodiment shown, a display container is provided for a half dozen small bottles, such as are used for table sauces. Some of these bottles A are indicated in phantom in Figures 3 and 4 in place in the container 1. They will be arranged in two tiers or rows on different levels, with three bottles in each tier. In Figure 3 only one bottle of each row is indicated, so as not to cause confusion with other lines of the drawing, but as is apparent, space is provided for three such bottles in each of two rows.

The blank, which will be die cut and scored by automatic machinery as is customary in the art, is conveniently formed of pasteboard which may be previously printed with advertising or

2

decorative matter in the manner well known in the art, and has the outline shown in Figure 1 of the drawing. In Figure 1 the boundaries of the blank and cuts within the blank are indicated in solid lines, while score lines for folding are indicated by dotted lines. The longitudinal score lines 3, 5, 7, 9, 11 and 13 divide the blank into seven panels 4, 6, 8, 10, 12, 14 and 16, the coaction and purposes of which will be hereinafter indicated more fully. Panel 6, in turn, is divided by transverse score lines 19 and 21 into subsections 20, 22 and 24, and a U-shaped cut 25 in sub-section 24 forms an ear or tab 26. A cut 19a is located centrally of the score line 19 to take a tab, later described. The panel 14 is in turn divided by cuts 27 and 29 continuing the boundary lines 31 and 33 of the adjacent panels 12 and 16. The cuts 27 and 29, together with transverse score line 35, defined a sub-section 34 of the panel 14. The cuts 27 and 29 and the transverse score lines 35, 37 and 39 divide panel 14 into sub-sections 34, 36, 38 and 40 and an arcuate cut 41 in the sub-section 40 forms a tab or ear 42.

The container is intended for automatic manufacture by mass production machinery of existing design, and for shipment to the customer in collapsed condition. Accordingly, the production of the container of Figures 3, 4 and 6 may conveniently be divided into two sets of operations, the first set being concerned with the manufacture of the collapsed container of Figure 2 and the second set being concerned with the setting up of this collapsed container, as indicated in Figures 3, 4 and 6.

In producing the collapsed container of Figure 2, the blank of Figure 1 is fed through an automatic machine, proceeding therethrough always in the direction of the longitudinal score lines 3, 5, etc. and being folded only on longitudinal score lines and continuously from one end to the other, in what may be termed the continuous roll-around principle. The side of the blank shown in Figure 1 will be arbitrarily called the "face" thereof, for definiteness in the following description.

The part 4, which has been referred to as a panel, is not a panel in the sense of forming a wall or partition of the completed container, but is merely an extension or flap provided for joining such walls or partitions together.

The first fold takes place along the line 5, panels 4 and 6 being folded over so as to lie face to face over panels 10 and 8. The second fold occurs on the line 9, bringing the reverse of panels 4 and 6 over panels 12 and 14. The reverse

of panel 4 will previously have been prepared with adhesive over an area indicated by the phantom outline 45. This last fold brings the adhesive on the reverse of panel 4 against panel 12, thus joining these two elements together. The last fold occurs on the line 13, panel 16 being folded over against part of the face of the panel 14 and the reverse of panel 8 and being joined to the latter by adhesive previously placed on its face, as indicated at 41. This completes the container in collapsed condition as shipped to the customer and as shown in Figure 2. While the last fold brings panel 16 over on the previously folded elements instead of vice versa, this being more convenient in the operation of the folding machinery, it will be observed that the effect is the same as though the previously folded structure had been folded over along line 13 onto the panel 16, the fold being in one direction so far as the blank is concerned, in either case.

In Figure 2, where the face (according to Figure 1) of the panel of Figure 1 is shown, that fact is indicated by the suffix "F" applied to the relevant reference numeral, and where the reverse is shown, that fact is indicated by the suffix "R." As will be apparent the reverse of the blank of Figure 1 forms the outside of the container and also forms the front or visible part of internal transverse elements, so that all printing and surface decoration may be done on the reverse of the blank of Figure 1.

In setting up the collapsed container of Figure 2, the customer will push or squeeze it together, applying pressure on fold lines 13 and 9, causing the container to open up into a rectangular tubular form, being open at both ends. Panel 6 forms the front and panel 10 forms the back, which will be parallel, and panels 12 and 16 form parallel sides, while panel 6 extends up the middle in parallelism to the front and back panels 14 and 10.

Neglecting small differences in dimensions due to the folding, it will be apparent that panels 6, 10 and 14 are of equal width, panels 12 and 16 are equal in width to each other, and panel 8 is half the width of panels 12 and 16. The variation introduced by the folding is merely to widen slightly the panels to the left of the blank of Figure 1 as compared with panels of substantially equal width to the right thereof.

The set-up, so far as panel 6 is concerned, is completed by folding this panel as indicated in Figure 4, the panel being folded on the transverse score lines 19 and 21, forming 90° angles between the sections 20, 22 and 24 and the flap 26 is slipped over the rear panel 10, holding the parts securely in proper vertical relation. The panel 14 is similarly folded on the three score lines 35, 37 and 39, and the tab 42 is slipped into the slot 19a cut in the middle of score line 19 on the panel 6, thus holding the sub-panels 36, 38 and 40 securely in proper vertical relation.

There has thus been formed out of a single blank and by a continuous roll-around operation adapted to high speed existing automatic machinery, a collapsed container, and this collapsed container, by utilizing merely the usual folding and fitting in of tabs involved in setting up paper boxes and the like, has been formed into a completed display container having two shelves or supporting surfaces 38 and 22 at different levels, for supporting two tiers of articles to be displayed and the two tiers of articles are in turn separated and held by the front and back walls and by an intermediate transverse partition.

The dimensional relations necessary for the proper fitting of the parts of panels 6 and 14 for obtaining the relationship of elements and angles as shown, are simple. The width of sub-section 22 (measured from score line 19 to score line 21) is of course equal to the width of panel 8 and the distance from score line 21 to the top of flap 26 as defined by the two ends of the cut, will equal the distance from score line 19 to the projection of the top boundary of the back panel 10. Similarly, the distance from score line 35 to score line 37 will equal the distance from score line 35 to the bottom boundary of the panel 14; the distance from score line 37 to score line 39 will be half the width of panel 12 and will be equal to the distance between score lines 19 and 21; while the distance from score line 39 to the base of the flap 42 as defined by the terminals of the cut 41, will in turn equal the height of the sub-section 20 of panel 6, or distance between the score line 19 and the bottom boundary of panel 6. In the case of these dimensions just discussed, such departure from equality as is involved or necessitated by the folds, is assumed to be made. This variation will be different with materials of different thickness but is readily determinable.

The structure as described is susceptible of very considerable variation to suit different products and requirements. A brief description of the dimensional changes required to adapt the container for other types of display will be sufficient to indicate to those skilled in the art how to effect any desired changes.

In the first place, while the shelves or supports 38 and 22 are shown as horizontal, this being the best form for displaying articles of the type indicated, it will be apparent that these shelves may be sloped frontwardly or rearwardly as desired. A rearward slope may be imparted to the shelf or front tier floor 38 by suitably decreasing the distance between score lines 35 and 37 and increasing that between score lines 37 and 39, while a forward slope may be imparted by increasing the distance between score lines 37 and 39 and suitably decreasing the distance between the flap 42 and the score line 39. Front or rear tilt may likewise be imparted to the shelf 22 by suitably repositioning score line 21 and tab 26.

Secondly, it might be desired to display articles of one character in the front tier and articles of another character in the rear tier and, in view of this, to make the depth of the tiers different. This would be accomplished by variation in the width of the panel 8 as compared with panels 12 and 16, with the location of the adhesive 45 to suit.

The panels 6, 10 and 14 should be in parallelism both in the collapsed container of Figure 2 and in the set-up container of the following figures, in order to provide for the collapse of the box. This implies that the distance from score line 5 to score line 9 will be equal to the distance from score line 9 to score line 13, again allowing for the small adjustment of dimensions to allow for the folds.

In the preferred form of the invention, it is intended to supply both a shipping container, as well as a display container. This permits the manufacturer to package his product and ship it in a form in which the retailer is not required to set up the box. This is desirable, since the setting up operation can be performed more efficiently by the manufacturer and also for the reason that shipment of collapsed containers

along with the articles to be sold, creates a danger of loss of containers. Accordingly, there is provided with the display container proper, as heretofore described, an outer carton 50 of generally rectangular form and having an inner L-shaped partition 51 to form a filler block. The display container is slid into the carton 50, as will be obvious from Figure 6, the bottles in the lower tier being held in position by the display container and outer carton with their tops against the filler block 51 and the bottles in the upper tier being held in position by the display container with their sides against the filler block 51 and their tops against the wall of the outer carton 50.

The display container may be used in the form shown without additional surfaces bearing advertising matter, or the sub-section 24 of the panel 6 may be elongated upwardly to any extent desired for carrying additional printing. Such elongation, however, tends to waste pasteboard and, accordingly where additional advertising surface is desired, it is preferred to provide a separate card or extension for the panel 6. This element 52, which is shown in Figure 5, may be generally rectangular and have a bendable tab 53, the bend occurring on score line 54. Tab 53 is L-shaped and has a vertical neck 55 and a lateral or horizontal extension 56. The tab 53 may be folded over on the score line 54 so that the element 52 may be inserted into the carton 50 along with the display container proper, 1, as indicated in Figure 6.

In this position the horizontal extension 56 of the tab is pulled up against the upper boundary of the cut 25 and the body of the card 52 is folded over the back of the container. In setting up, the card 52 is raised to the vertical position and is then pressed down to the front of the panel 24 until it seats against the bottom boundary of the cut 25.

What is claimed is:

1. A display container blank comprising a series of six aligned panels defined and separated from each other by parallel score lines for folding, the blank being adapted for folding continuously in one direction to form the container and comprising panels for forming a rectangular outer sleeve and a partition wall parallel to opposed side panels of the sleeve and dividing the same into two compartments, the panel which is to form the partition wall having one connected side flap element foldable transversely of the blank to form a shelf in one of the said compartments, and a flap hinged thereto and lying against the outer wall of the compartment and having a cut out forming a tongue for engaging over the top of said wall to hold the shelf in position.

2. A display container according to claim 1 comprising also transversely foldable flap elements on a side wall panel and including an element foldable downwardly to lie against the side wall and inside the same, a second element connected thereto and foldable to lie horizontally, and a third element connected to the second element and foldable to extend vertically against the partition wall and having a cut-out defining a tongue for fitting thereover to hold the second element in position, the blank being formed with a cut in the partition wall panel for receiving the tongue of the said third element.
3. A display container comprising a one piece blank folded continuously in one direction and having a series of six panels connected to each other along parallel fold lines, the panels forming a rectangular outer sleeve and a partition parallel to opposite sides thereof which divides the same into two compartments and having also transversely folded elements attached to the partition and to one of the said side walls and forming shelves in the two said compartments at different elevations for displaying goods in two tiers while providing visibility for each tier, and the transversely folded elements including elements having cut outs forming tongues engaging over the top of the partition and a side wall for holding the shelves in position.
4. A display container comprising a one piece blank folded continuously in one direction and having panels forming a rectangular outer sleeve and a partition parallel to opposite sides thereof which divides the same into two compartments and having also transversely folded elements attached to the partition, the said transversely folded elements comprising a first horizontal element connected to the partition and forming a shelf in one of the said compartments, and a vertical second element connected to the horizontal element and lying along the outside wall of the partition, the said vertical element having a cut out forming a tongue engaging over the top of the outside wall to hold the shelf in position.
